United States Patent Office

Des. 227,196
Patented June 12, 1973

227,196

DIVING HELMET

Charles E. Griswold, Box 976, Seattle, Wash. 98111

Filed Dec. 23, 1971, Ser. No. 211,820

Term of patent 14 years

Int. Cl. D2—03

U.S. Cl. D2—232

Fig. 1

Fig. 2

Fig. 3

Fig. 4

FIG. 1 is a front perspective view of a diving helmet showing my new design;

FIG. 2 is a side elevation view;

FIG. 3 is a front elevation view; and

FIG. 4 is a top plan view.

Parts of the design have been shaded for transparency.
I claim:

The ornamental design for a diving helmet, as shown and described.
